Primary Examiner — Richard E Chilcot(57) **CLAIM**

The ornamental design for a multi functional flashlight, as shown and described.

DESCRIPTION

FIG. 1 is a perspective view of a flashlight showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second state of the flashlight thereof;

FIG. 9 is a perspective view of a third state thereof;

FIG. 10 is a perspective view of a separated state thereof.

FIG. 11 is an enlarged view of the selected portion in FIG. 1; and,

FIG. 12 is an enlarged view of the selected portion in FIG. 3.

The broken lines shown in the drawings depict portions of the flashlight in which the design is embodied that form no part of the claimed design.
